US00D877366S

(12) **United States Design Patent** (10) Patent No.: **US D877,366 S**
(45) Date of Patent: **** Mar. 3, 2020**

(54) **RECHARGEABLE DISC NIGHT VISION
LAMP**

(71) Applicant: **Shenzhen Guandexin Technology CO.,
LTD**, Shenzhen (CN)

(72) Inventor: **Shaobo Deng**, Shenzhen (CN)

(73) Assignee: **Shenzhen Guandexin Technology Co.,
Ltd. (CN)**

(**) Term: **15 Years**

(21) Appl. No.: **29/678,720**

(22) Filed: **Jan. 30, 2019**

(51) LOC (12) Cl. **26-05**

(52) U.S. Cl.

USPC **D26/26**

(58) **Field of Classification Search**
